CLAIM

The ornamental design for a decorative article, as shown and described.

DESCRIPTION

FIG. 1 is a perspective view of a decorative article according to the present invention;

FIG. 2 is a front view of the decorative article of FIG. 1; FIG. 3 is a back view of the decorative article of FIG. 1; FIG. 4 is a right side view of the decorative article of FIG. 1, the left hand view being the mirror image thereof; FIG. 5 is a top plan view of the decorative article of FIG. 1; and,

FIG. 6 is a bottom plan view of the decorative article of FIG. 1.

The structure depicted by means of broken lines in the figures has been shown for illustrative purposes only and forms no part of the claimed design.

The appearance within the crown arch outline shown in FIGS. 3 and 5 forms no part of the claimed design.
